THREAD CUTTING DIE

Luben Nikoloff, Boston, Mass.

Application October 15, 1930, Serial No. 488,833

19 Claims. (Cl. 10—120)

This invention relates to a thread-cutting die having certain novel and improved features, namely, first, thread-cutting chasers which may be removed when worn or broken and replaced by new ones; and second, hard inserts set into the body of the die stock to receive the wear of the chasers. There are disclosed in this application several novel features which are not claimed herein, namely, first, means for adjusting the body and consequently the chasers to vary the diameter of the screw to be cut; second, a blank guide which is axially adjustable with relation to the body, and in the case of an adjustable body is self-adjusting to compensate for adjustment of the body; third, improved handles by which the die stock is manipulated; and fourth, a bevel at the first end of the chaser to bevel off the end of the blank or stock, in case the latter is somewhat over-size. These features are the subject matter of a divisional application.

The invention will best be understood by reference to the following description, when taken in connection with the accompanying drawings of three illustrative embodiments thereof, while its scope will be pointed out more particularly in the appended claims.

In the drawings:

Fig. 1 is an elevation, partly in vertical section, of one form or embodiment of the invention; Fig. 2 is an elevation at an enlarged scale of a portion of Fig. 1;

Fig. 3 is a sectional view on line 3—3 of Fig. 2;

Fig. 4 is a sectional view on line 4—4 of Fig. 2;

Fig. 5 is a sectional view on line 5—5 of Fig. 2;

Fig. 6 is a perspective view of one of the thread-cutting chasers shown in Figs. 1 to 5, inclusive;

Fig. 7 is an elevation, partly in vertical section, of a second form or embodiment of the invention;

Fig. 8 is an elevation, at an enlarged scale, of a portion of Fig. 7;

Fig. 9 is a sectional view, on line 9—9 of Fig. 8;

Fig. 10 is a sectional view on line 10—10 of Fig. 8;

Fig. 11 is a sectional view on line 11—11 of Fig. 8;

Fig. 12 is a sectional view on line 12—12 of Fig. 8; and

Fig. 13 is a perspective view of one of the thread-cutting chasers shown in Figs. 7 to 12, inclusive.

Referring to the form of the invention which is illustrated in Figs. 1 to 6, inclusive, of the drawings, and having reference at first more particularly to Fig. 1, there is shown a thread-cutting die comprising a body 21, provided with

a blank-receiving opening 22, and a plurality of chaser-receiving slots 23. In this example, there are four of these slots, each of which receives a thread-cutting chaser 24, though the number will depend somewhat upon the diameter of the stock or blank to be threaded. The number will vary from three to six or more in practice, but of course the design of the body or holder may have to be varied to suit the number of chasers.

One important feature of my invention which characterizes both forms is that the body and the chasers have sidewise interengaging means restraining the chasers against movement lengthwise of the axis of the die, and providing for attachment of each chaser to the body by movement of the chaser, first in one direction and then in another direction to a position in which the chaser is interengaged with the body, and restrained against movement lengthwise of the axis. To this end, in the form shown in Figs. 1 to 6, inclusive, the slots are radial, and have laterally widened portions, as by being provided with a plurality of pairs of grooves 25, one pair associated with each slot, the two grooves of each pair leading laterally in opposite directions, respectively, from the associated slot, said grooves extending lengthwise of the axis of the die.

In this form, each chaser is provided with two sets of oppositely and sidewise projecting tongues (best shown in Fig. 6), interengaged with the body, each set of tongues on each chaser comprising two pairs of tongues 26 and two pairs of tongues 27, four overlying one face of the body and four overlying the opposite face. The width of each tongue 26 in a generally radial direction is somewhat less than the width of each groove 25, and the tongues 26 and 27 are separated by spaces 28, whose width is somewhat greater than the distance between the groove 25 and the central opening 22. As a consequence, each chaser is detachable from the body by sliding radially along its slot toward the central opening to bring the two pairs of tongues 26 into registration with the respective laterally widened portions of the slot, i. e., the grooves 25 on opposite sides of the slot, and to bring the other two pairs of tongues 27 into registration with the central opening. This movement unlocks the chaser, and permits the latter to slide in its slot lengthwise of the axis of the die. During this sliding movement, the tongues 26 of one pair slide through the grooves 25, while the tongues 27 of one pair pass through the central opening 22. Thus, any or all of the chasers when worn or broken may be removed and replaced by new ones.

As the body will be made of a comparatively soft grade of steel, capable of flexing in the manner presently to be described, without danger of crystallizing and cracking, the body may be, 5 and herein is, provided with sets of relatively hard inserts, such as cylindrical pins, comprising two pairs of pins 29 and two pairs of pins 30, to receive the wear of the chasers. Each tongue 26 overlies a pin 29, and each tongue 27 overlies a 10 pin 30, as will be evident from a comparison of Figs. 2 and 5.

To retain the chasers in their proper positions in their respective slots, there is associated with each chaser a suitable retainer, herein a screw 15 31 extending loosely through a radial hole 32 in the body, and having screw-threaded engagement with a threaded hole 33 (best shown in Fig. 6) in the chaser. By first removing these screws, the chasers may be dismounted from the body 20 in the manner hereinbefore described.

Another feature of the invention now to be described is means for adjusting the body, and consequently the chasers, to vary the diameter of the screw to be cut. To this end, in the form 25 of the invention illustrated in Figs. 1 to 6, inclusive, the body is rendered expansible and contractible by providing the same with two slots 34 (see Fig. 2), leading in opposite directions from the central opening 22, or it may be considered that there is a single slot interrupted by 30 the central opening. To increase the flexibility of the holder, each slot at its outer end terminates in an opening 35, herein cylindrical. Thus, the body is quite thin on opposite sides of these 35 openings, and is capable of bending with the requisite degree of freedom.

Adjustment of the holder by flexing the same is conveniently accomplished by the use of tapered adjusting screws 36 (best shown in Fig. 3), 40 threaded into the body. These screws may be and herein are provided with hexagonal sockets 37, to receive a tool by means of which they may be turned. By turning the screws in the proper direction, the body may be expanded or allowed 45 to contract at will, thereby furnishing an adjustment to vary the diameter of the screw to be cut by the chasers.

To prevent the adjustment from being disturbed accidentally, I have provided two clamping 50 screws 38, associated with the slots 34, respectively, and adapted to clamp the body about the adjusting screws 36 to prevent rotation of the latter. As shown, each clamping screw is provided at one end with a head 39, and extends, 55 first loosely through an opening 40 at one side of the slot 34, then across the slot, then into a screw-threaded opening 41, with which it has screw-threaded engagement. As a measure of safety, to prevent the clamping screw from being 60 screwed so far as to cause danger of breakage of the body, and further, as a means to prevent loss of the clamping screws, each in the present example is provided with a safety stop 42, normally separated from the adjacent side of the 65 body by a space 43. Each stop is conveniently secured to its screw by providing the latter with a reduced portion 44 to receive the stop, and the outer end of the screw is headed over or riveted, as at 45, to hold the stop in place.

70 Another feature of the invention which may be termed a blank guide will now be described, reference being had to Fig. 4. This guide is for the purpose of guiding the blank or stock, and holding the same properly centered with relation to the chasers. As shown, the guide com-

prises a plate 46, provided with an aperture 47 whose diameter is such that the blank or stock just slides freely through it, and is accurately centered. This plate is conveniently mounted for adjustment on the body by providing the latter with holes 48 lengthwise of the axis of rotation of the die to receive slidable pins 49, which may be clamped in any desired position within the range of adjustment by set screws 50, herein having knurled heads 51 to enable them to be 85 turned with the fingers.

One of the pins 49 is permanently and rigidly affixed to the plate 46, as by providing the same with a reduced portion 52 passed through the plate, and riveted as at 53. Inasmuch as this particular die has an adjustable body, the remaining pin 49 is self-adjusting to compensate for adjustment of the body. This is conveniently accomplished in the present example by providing the remaining pin with a reduced portion 54, which extends through a radial, elongated slot 55 in the plate 46, the reduced portion extending thence through and secured as by riveting at 56 to a block 57, which is slidably radially in a groove 58 provided in the plate. Thus, the pin is capable of moving radially with relation to the plate when the body is being adjusted.

Referring to Fig. 5, it will be observed that the chaser is provided with, not only the usual chamfer represented by the line A—A, but also a bevel, 105 represented by the line B—B (which may be either round or straight), herein round, the purpose of which is to bevel off the end of the blank or stock, in case the latter is somewhat over size. This prevents the tearing and spoiling of threads, 110 which sometimes occurs when the stock is somewhat larger than it should be.

In this form of the invention, the body is provided with handles 59, which are integral therewith and of cylindrical form. As shown, these 115 handles are lightened by drilling holes 60 (see the left-hand portion of Fig. 1) lengthwise of the handles. When the handles are short, it is desirable to provide the outer end of each with a rounded terminal portion in the form of a cap 120 61 to prevent injury to the palms of the hands. This cap is conveniently attached to the handle by providing the cap with a tapered portion 62, which merges into the cylindrical surface of the handle, and is conveniently secured to the latter, 125 as by welding.

The second form or embodiment of the invention will now be described, reference being had to Figs. 7 to 13, inclusive. In this form, there is a body 63, having a central opening 64 to receive the blank or stock, and a plurality of chaser-receiving slots 65, which as shown are four in number, and radially disposed. Each of these slots receives a thread-cutting chaser 66, which, like the chasers of the first form, is interengaged 135 sidewise with the body. In this form, however, the chaser is flush at its ends with the faces of the body (see Fig. 11). Interengagement of the chaser and the body in this case is had by providing the chaser with two sets of tongues or teeth 67 and 68 (see Figs. 12 and 13), interengaged with correspondingly-shaped teeth on the body. The latter is provided with lateral grooves 69, one associated with each slot 65, and extending lengthwise of the axis of the die, the width of each groove in a radial direction being somewhat greater than the width of the tongues or teeth 67. The chaser is provided with a groove or space 70, between its two sets of tongues or teeth, and the width of this space is somewhat 145 150

greater than the distance from the groove 69 to the central opening 64. As a result, the chaser may be dismounted from the body by sliding the chaser radially inward to bring the tongues or teeth 67 into registration with the groove 69, and to bring the tongues or teeth 68 into registration with the central opening 64, thus unlocking the chaser from the body and permitting the chaser then to slide in the slot 65 lengthwise of the axis 5 of the die. To facilitate machining the tongues or teeth in the body, the latter as shown is provided with grooves 71, adjacent the outer ends of the slots 65 (see Fig. 8). Here, as in the first form, the chasers are normally secured in place by radial screws 72.

In this form of the invention, as in the first, the body is adjustable; but in this form, the means of adjustment, while having a general resemblance to the first form, differs somewhat 10 in detail, more specifically by the employment of a single adjusting screw and a single clamping screw. Referring to Fig. 8, the body is rendered flexible by providing the same with two slots 73 and 74, the former being straight and the latter 20 having an oblique portion 75, which extends to the side of the body. The slot 73 terminates at its outer end in an opening 76 to increase the flexibility. In this case, as already intimated, there is a single tapered adjusting screw 77, 30 threaded into the body, and there is a single clamping screw 78. As these screws are like the corresponding screws of the first form, it is deemed unnecessary to describe them in detail.

This form, like the first, is provided with a 35 blank guide (best shown in Fig. 10), which in all respects is like that of the first form, and therefore needs no description.

In this form, the die is provided with tubular handles 79, having terminal caps 80 like those of the first form, but in this form, each handle is 40 detachably secured to the body by providing the latter with a reduced threaded portion 81, upon which is screwed a thimble 82, the latter having a reduced portion 83 inserted into the tubular handle, and suitably secured therein as by welding at 84.

Having thus described two embodiments of the invention, but without limiting myself thereto, what I claim and desire by Letters Patent to secure is:

1. In a thread-cutting die, the combination of a body provided with a blank-receiving opening, a plurality of chaser-receiving slots leading from said opening, and a plurality of sidewise grooves leading from said slots, respectively, transversely of radial planes containing the axis of said opening, and a plurality of chasers received in and engaging both sides of said slots, respectively, said chasers being provided with sidewise projections interengaging sidewise with said body transversely of said planes, each chaser being detachable from said body by movement in its slot radially inwardly to a position in which its projection registers with the groove leading sidewise from such slot and then enters and finally leaves such slot by movement lengthwise of the axis of said blank-receiving opening.

2. In a thread-cutting die, the combination of a body provided with a blank-receiving opening, a plurality of chaser-receiving slots leading from said opening, and a plurality of chasers received in and engaging both sides of said slots, respectively, said body and said chasers being provided with sidewise interengaging, cooperative means 75 providing for detachment of each chaser from said

body by movement of such chaser inwardly toward the axis of the die and then longitudinally of said axis, said means including projections extending sidewise from said chasers, and transversely of said slots, considered with reference to radial planes containing said axis. 80

3. In a thread-cutting die, the combination of a body provided with a blank-receiving opening, a plurality of chaser-receiving slots leading from said opening, and a plurality of chasers received in and engaging both sides of said slots, respectively, said body and said chasers being provided with sidewise interengaging, cooperative means normally preventing movement of such chaser lengthwise of the axis of the die, and providing for detachment of such chaser from said body by movement of such chaser first to a position in which it can move lengthwise of said axis and then movement lengthwise of said axis, said means including projections extending sidewise from said chasers and transversely of said slots considered with reference to radial planes containing said axis. 90

4. In a thread-cutting die, the combination of a body provided with an axial, blank-receiving opening, a plurality of chaser-receiving slots leading from said opening, and a plurality of pairs of sidewise grooves, one pair associated with each slot, the two grooves of each pair leading laterally in opposite directions, respectively, from the associated slot, and a plurality of thread-cutting chasers received in and engaging both sides of said slots, respectively, each chaser being provided with a pair of oppositely projecting tongues interengaged sidewise with said body, each chaser being detachable from said body by sliding along its slot toward said opening to bring its tongues into registration with the respective grooves leading from such slot, such chaser being then slidable in its slot lengthwise of the axis of the die. 100

5. In a thread-cutting die, the combination of a body provided with an axial, blank-receiving opening, a plurality of chaser-receiving slots leading from said opening, and a plurality of pairs of sidewise grooves, one pair associated with each slot, the two grooves of each pair leading laterally in opposite directions, respectively, from the associated slot, and a plurality of thread-cutting chasers received in and fitting both sides of said slots, respectively, each chaser being provided with two pairs of sidewise, oppositely projecting tongues interengaged sidewise with said body, each chaser being detachable from said body by sliding along its slot toward said opening to bring one pair of tongues into registration with the respective grooves leading from such slot and to bring its other pair of tongues into registration with said opening, such chaser being then slidable in its slot lengthwise of the axis of the die. 110

6. In a thread-cutting die, the combination of a body provided with an axial, blank-receiving opening, a plurality of chaser-receiving slots leading from said opening, and a plurality of pairs of sidewise grooves, one pair associated with each slot, the two grooves of each pair leading laterally in opposite directions, respectively, from the associated slot, and a plurality of thread-cutting chasers received in and fitting both sides of said slots, respectively, each chaser being provided with two sets of sidewise oppositely projecting tongues interengaged sidewise with said body, each set comprising two pairs of sidewise tongues, each chaser being detachable from said body by sliding along its slot toward said opening to bring one set of tongues into registration with the respec- 120

130

140

145

150

- tive grooves leading from such slot and to bring the other set of tongues into registration with said opening, such chaser being then slidale in its slot lengthwise of the axis of the die.
- 5 7. In a thread-cutting die, the combination of a body provided with a blank-receiving opening, a plurality of chaser-receiving slots and a plurality of sidewise grooves leading from said slots, respectively, considered with reference to radial planes 80 containing the axis of said opening, and a plurality of chasers received in and fitting both sides of said slots, respectively, each chaser being provided with a sidewise projection interengaging sidewise with said body between opposite end faces of said body, each chaser being detachable from said body by movement inwardly toward said opening, which movement interrupts the interengagement of its projection with said body and brings such projection into registration with 85 the groove leading from the slot in which such chaser is received, and then movement of such chaser lengthwise of said axis, which movement carries such projection along said groove.
8. In a thread-cutting die, the combination of a body provided with a blank-receiving opening, a plurality of chaser-receiving slots and a plurality of sidewise grooves leading from said slots, respectively, considered with reference to radial planes containing the axis of said opening, and 90 a plurality of chasers received in and fitting both sides of said slots, respectively, each chaser being provided with two sidewise projections interengaging sidewise with said body between opposite end faces of the latter, each chaser being detachable from said body by movement inwardly toward said opening, which movement interrupts the interengagement of its projections with said body and brings one projection into registration with the groove leading from the slot in which 95 such chaser is received, and then movement of such chaser lengthwise of said axis, which movement carries one projection along such groove and the other along said opening lengthwise of the axis of the die.
- 45 9. In a thread-cutting die, the combination of a body provided with a blank-receiving opening, and a plurality of chaser-receiving slots leading outwardly from said opening, a plurality of chasers received in and engaging both sides of said 100 slots, respectively, said body and said chasers having sidewise interengaging means interengaging sidewise with reference to radial planes containing the axis of said opening and normally restraining said chasers against movement lengthwise of the axis of the die, said means including 105 projections extending sidewise from said chasers and transversely of said slots, and means normally to maintain such interengagement.
10. In a thread-cutting die, the combination of a body having opposite parallel faces, a blank-receiving opening and a plurality of chaser-receiving openings, a plurality of hard inserts set into said body from both of said faces, and a plurality of chasers received in said chaser-receiving openings, respectively, and having projections outwardly beyond said faces and contacting with said inserts.
11. In a thread-cutting die, the combination of a body provided with a central opening and a plurality of radial openings leading from said central opening, and a plurality of thread-cutting chasers received and slidale radially in and engaging both sides of said radial openings, respectively, and projecting into said central opening, the radial dimension of each chaser being greater 145 than the root diameter of the thread to be cut by said chasers, each chaser having means normally interlocked sidewise with said body and preventing movement of such chaser lengthwise of the axis of rotation of the die, said means including projections extending sidewise from said chasers and transversely of said radial openings, each chaser being movable radially inwardly a distance less than its radial dimension to bring a portion of such chaser within the circle of said diameter and to unlock said chaser from said body.
12. In a thread-cutting die, the combination of a body provided with a central opening and a plurality of other, radial openings communicating with said central opening and having closed, outer ends, a plurality of thread-cutting chasers movably mounted in said other openings, respectively, and projecting into said central opening, the radial dimension of each chaser being greater than 150 the root diameter of the thread to be cut by said chasers, the outer end of each chaser engaging the closed, outer end of the opening in which it is mounted, each chaser having sidewise projecting means which extends transversely of the axis of rotation of the die and transversely of said other openings, and normally prevents movement of such chaser longitudinally of said axis, each chaser being movable radially inwardly a distance less than its radial dimension to bring a portion of such chaser within the circle of said diameter and to unlock said chaser from said body.
13. In a thread-cutting die, the combination of a body having opposite, generally parallel faces, said body being provided with a blank-receiving opening and a plurality of generally radial, chaser-receiving slots extending from one of said faces to the other, and a plurality of thread-cutting chasers received in and having portions engaging portions of both sides of said chaser-receiving slots, respectively, said chasers having exposed faces corresponding to said faces of said body, said chasers and said body having interengaging means normally restraining said chasers against movement lengthwise of the axis of said blank-receiving opening, said means including projections, certain of which extend sidewise from said chasers and transversely of said sides of said slots, each chaser being removable from its slot by sliding the same freely inwardly toward said blank-receiving opening to bring its said sidewise extending projections fully into registration with said blank-receiving opening and its remaining projections into registration with a portion of its slot, and then moving said chaser lengthwise of said axis out of said body.
14. In a thread-cutting die, the combination of a body having opposite, generally parallel faces, said body being provided with a blank-receiving opening and a plurality of generally radial, chaser-receiving slots extending from one of said faces to the other, said body being also provided with a plurality of grooves extending from one of said faces to the other lengthwise of the axis of said blank-receiving opening and leading sidewise from said slots, and a plurality of thread-cutting chasers received in and engaging both sides of said chaser-receiving slots, respectively, said chasers having exposed faces corresponding to said faces of said body, said chasers having means interengaging with said body and normally restraining said chasers against movement lengthwise of said axis, said means including projections overlying said faces and normally out of registration with said grooves, each chaser being removable from its slot by sliding the same freely 130

- inwardly toward said blank-receiving opening to bring its said projections into registration with the groove leading from its slot, and then moving said chaser lengthwise of said axis to cause one 5 of its said projections to pass through such groove and out of said body.
15. In a thread-cutting die, the combination of a body having opposite, generally parallel faces, said body being provided with a blank-receiving opening and a plurality of generally radial, chaser-receiving slots extending from one of said faces to the other, a plurality of thread-cutting chasers received in and having portions engaging portions of both sides of said chaser-receiving slots, respectively, said chasers having exposed faces corresponding to said faces of said body, said chasers and said body having interengaging means normally restraining said chasers against movement lengthwise of the axis of said blank-receiving 10 opening, said means including projections, certain of which extend sidewise from said chasers and transversely of said sides of said slots, each chaser being removable from its slot by sliding the same freely inwardly toward said blank-receiving opening to bring its said sidewise extending 15 projections fully into registration with said blank-receiving opening and others into registration with a portion of its slot, and then moving said chaser lengthwise of said axis out of said body, and means normally to secure said chasers against such inward sliding movement.
16. In a thread-cutting die, the combination of a body having opposite, generally parallel faces, said body being provided with a blank-receiving opening and a plurality of generally radial, chaser-receiving slots extending from one of said faces to the other, and a plurality of thread-cutting chasers received in and engaging both sides of said chaser-receiving slots, respectively, said 20 chasers having exposed faces corresponding to said faces of said body, said chasers and said body having interengaging means providing for detachment of each chaser from said body by movement of such chaser first radially inwardly toward said opening to a position in which such chaser is in part at least within said opening and is unlocked from said body, and subsequently lengthwise of the axis of said opening, said means including projections extending sidewise from said 25 chasers and transversely of radial planes containing said axis.
17. In a thread-cutting die, the combination of a body provided with a blank-receiving opening, a plurality of chaser-receiving slots leading from 30 said opening, and a plurality of chasers received in and engaging both sides of said slots, respectively, said chasers and said body being provided with interengaging means including a front projection and a rear projection on each chaser, 35 said projections being of such dimensions and so arranged that when such chaser is moved radially inwardly until said front projection is wholly within said opening, such chaser may be moved lengthwise of the axis of said opening, said front 40 projection passing axially therethrough, and said rear projection passing through an enlarged portion of its respective chaser-receiving slot.
18. In a thread-cutting die, the combination of a body having opposite, generally parallel faces, said body being provided with a blank-receiving opening and a plurality of generally radial, chaser-receiving slots extending from one of said faces to the other, and a plurality of thread-cutting chasers received in and having portions engaging portions of both sides of said chaser-receiving slots, respectively, said chasers having exposed faces corresponding to said faces of said body, said chasers and said body having interengaging means normally restraining said chasers against movement lengthwise of the axis of said blank-receiving opening, said means including projections extending sidewise from said chasers and transversely of the sides of said slots, and including also other projections disposed radially outwardly with relation to the first-mentioned projections, each chaser being removable from its slot by sliding the same freely inwardly toward said blank-receiving opening to bring its first-mentioned projection fully into said blank-receiving opening and to bring its second-mentioned projection into an enlarged portion of said slot, and then moving said chaser lengthwise of said 55 axis out of said body.
19. In a thread-cutting die, the combination of a body provided with a blank-receiving opening, a plurality of chaser-receiving slots leading from said opening about the latter, and a plurality of chasers received in and having portions engaging portions of both sides of said slots, respectively, said chasers and said body being provided with interengaging means including a front projection and a rear projection on each chaser, 60 said projections being of such dimensions and so arranged that when such chaser is moved radially inwardly until said front projection is wholly within said opening, such chaser may be moved lengthwise of the axis of said opening, said front projection passing axially therethrough, and said rear projection passing through an enlarged portion of its respective chaser-receiving slot.
